Fixture

Wilson W. Hargrett, Wyandotte, William Trall, Dearborn, Clark A. Kureth, Flat Rock, and Glen Van Fleet, Wyandotte, Mich., assignors to Hargrett's Small Parts Machining, Wyandotte, Mich., a firm

Application April 10, 1947, Serial No. 740,644

2 Claims. (Cl. 90—60)

1
This invention relates to improvements in fixtures for holding workpieces for drilling, tapping, milling, grinding and sundry other operations. It is an object of the invention to provide such a fixture including an anvil and a movable button for holding a workpiece between them wherein the length of movement imparted to the button is constant though adjustment may be easily and quickly made so that there is any required distance between the button and the anvil after advancement of the former toward the latter. In this manner we aim to provide a fixture which may be quickly set to hold workpieces of different widths without resorting to feed screws for advancing or withdrawing the button toward or from the anvil.

Another object of the invention is to provide such a fixture including a cam rotatable through 90 degrees for advancing the button toward the anvil, spring means for moving the button away from the anvil as the cam is rotated through another 90 degrees, and wherein the cam is so shaped that pressure exerted against it by the spring does not impart any rotary movement thereto so that there is no fear of the button accidentally moving away from the anvil while a workpiece is held between them.

Another object of the invention is to provide such a fixture wherein both the anvil and the button are readily adjustable about their axes so that the face of a workpiece to be machined may be supported at any desired inclination.

Having thus briefly and broadly stated some of the objects and advantages of the invention, we will now describe a preferred embodiment thereof with the aid of the accompanying drawings, in which:

Figure 1 shows a plan view of the invention, Figure 2 is a side view thereof, and Figure 3 is an end view.

Figures 4, 5 and 6 are sections on the line 4—4, 5—5 and 6—6 respectively of Figure 2.

Figure 7 is a section on the line 7—7 of Figure 1.

Figure 8 is a detail plan view showing a horizontally supported workpiece one extremity of which bears against an adjustable stop plate, and

Figure 9 is an end view thereof.

Figure 10 shows a workpiece of square section held between the anvil and the button, the form

of the work engaging face of the latter being somewhat changed, and

Figure 11 shows a hexagonal workpiece similarly supported with the work engaging face of the anvil of different form to that shown in Figures 1 and 10.

Referring to the drawings, 1 designates a base having two spaced, aligned bearings 2 and 3 integral therewith. One side of the bearing 2 is preferably split at 4 and extending through the split portion and in threaded engagement with the main part of the bearing are screws 5 so that when the latter are tightened a housing 6 extending through the said bearing and projecting beyond both extremities thereof is held immovable. The housing 6 has an enlarged end 7 at its extremity remote from the bearing 3, and formed radially through the said enlarged end is an opening 8. Mounted for rotation in the latter is a cam shaft 9 which is held against axial movement by a pin 10 projecting into the enlarged end 7 and across an annular groove 11 formed in the said shaft. The housing 6 is tubular from its extremity adjacent the bearing 3 for the major portion of its length so that one side of a cam 12 formed on the cam shaft 9 extends across the inner extremity of the bore of the housing.

Mounted for axial movement in the bore of the housing 6 is a spindle 13 which at all times projects forwardly from the said housing toward the bearing 3, and terminates at its opposite extremity in a projection 14 of reduced diameter which bears against the cam 12. The spindle 13 is also bored from its extremity adjacent the bearing 3 and has a helical spring 15 therein one end of which bears against the inner extremity of the spindle bore while its opposite extremity rests against a pin 16 secured in opposite sides of the tubular portion of the housing 6 and extending through opposed longitudinal slots 17 formed through opposite sides of the tubular portion of the spindle.

The cam 12 has a flat face 12a on one side which is centrally disposed between two diametrically opposed arcuate rises 12b of substantially the same diameter as that of the shaft 9. When the latter is so turned that the projection 14 bears against one of the rises 12b the spindle 13 is pushed forward and the spring 15 is compressed; however due to the length and curvature of these

rises 12b there is no tendency for the shaft 9 and its cam 12 to turn under pressure of the spring so the spindle remains stationary in its forward or outwardly projecting position. As the shaft 9 and cam 12 are turned so that the flat face 12a is brought behind the projection 14 the spindle 13 is moved rearwardly by the spring 15 and consequently the said projection remains at all times in contact with the cam 12.

Extending radially through the spindle 13 adjacent its tubular extremity is a set screw 18 which engages the shank 19a of a button 19, and extending through the bearing 3 in axial alignment with the spindle 13 is an opening 20 in which the shank 21a of an anvil 21 is supported. The anvil 21 is held immovable in the bearing 3 in the present instance by a screw 22 which engages a threaded opening 23 formed in the shank 21a from its outer extremity; a washer 24 through which the screw 22 extends rests against the outer face of the bearing 3. The anvil 21 is usually provided with a V-shaped slot therein as shown to receive one side of a workpiece A to be held immovable between it and the movable button 19. The latter is usually V-shaped at its front extremity to extend into the slot in the anvil 21 and grip a workpiece, though the V-shaped extremity of the button may be indented as shown at 19b in Figures 10 and 11 to engage one corner of a multi-sided workpiece. By loosening the screws 18 and 22 the button 19 and anvil 21 respectively may be turned to support a workpiece A which extends either horizontally as shown in Figures 8 and 9, or vertically as shown in Figures 1 and 2, or at any other desired inclination.

Extending upwardly from the base 1 and in threaded engagement therewith is a stop 25 beneath the block 21 to support the lower extremity of the workpiece. Thus by rotating the stop the distance between its upper face and the axis of the anvil may be adjusted, and by tightening a lock nut 26 in threaded engagement with the stop 25 against the top of the base 1 the stop may be secured against accidental movement. Formed horizontally through the bearing 3 is an opening 27 having a rod 28 axially slidably therein, and 29 denotes a set screw in threaded engagement with the said bearing and projecting into the opening 27 to hold the rod 28 immovable. Integral with the outer extremity of the rod 28 is a stop plate 30 which extends at right angles thereto and may be employed for setting a horizontal workpiece A so that one extremity of the latter projects a predetermined distance from the button 19 and anvil 21 between which it is held.

In order to facilitate rotation of the cam shaft 9 under various operating conditions a plurality of openings 31 angularly disposed to one another are formed through the said shaft to receive a lever 32. The latter is inserted through one of these openings and is then held against axial movement by a screw 33 in engagement with a tapped hole 34 extending axially into the cam shaft 9 from its outer extremity.

The operation of the fixture is as follows: The screws 5 are loosened to permit axial movement of the housing 6 which is then adjusted to provide such spacing between the button 19 and the anvil 21 that the workpiece A will be securely held between them when the projection 14 is in contact with one of the cam rises 12b, that is when the spindle 13 is in its forward position. Then the screws 5 are tightened and the cam shaft 9 is turned through 90 degrees so that the

spindle 13 is moved rearwardly by the spring 15 and the projection 14 brought into contact with the flat cam face 12a. However before tightening the screws 5 the housing 6 may also be rotarily set so that the button is inclined at any desired inclination, instead of making rotary adjustment by turning the shank 19a in the spindle 13. The anvil 21 is then turned to a corresponding rotary position after first loosening the screw 22. Either the stop 25 or the stop plate 30 may then be adjusted so that one extremity of a workpiece bears against it when the said workpiece is properly positioned for performance of an operation thereon.

The bearing face 12a of the cam is disposed at right angles to the rises 12b and both the face and the rises are so formed that there is no tendency for the cam to be rotated by pressure exerted by the projection 14 against it. The cam shaft may be turned in either direction to disengage the workpiece, and, due to the provision of a plurality of angular openings through the cam shaft for the lever 32 the latter may be so arranged that it projects in any one of several different directions either when the workpiece is engaged or disengaged. Thus the path followed by the lever may be readily arranged to clear any projections on the workpiece.

While in the foregoing the preferred embodiment of the invention has been described and shown, it is understood that alterations and modifications falling within the scope of the claims may be made thereto.

What we claim is:

1. A fixture including a base having a bearing thereon, a housing tubular from one extremity axially adjustable through the bearing, means for holding the housing immovable in the bearing, a spindle axially movable in the housing and projecting outwardly beyond the tubular extremity of the latter, a cam shaft rotatably mounted in the housing, a cam on said shaft adapted to engage the extremity of the spindle remote from its outwardly projecting extremity and move it outwardly through the housing, said spindle being tubular from its outwardly projecting extremity for a portion of its length, the tubular spindle portion having opposed slots therethrough intermediate of its length, a pin transversely mounted in the housing and extending through the slots to permit axial movement of the spindle, a spring in the tubular portion of the spindle extending between the pin and the base of said tubular portion to retain the spindle against the cam, a button on the tubular extremity of the spindle, and an anvil supported on the base opposite the button between which and said button a workpiece is adapted to be held.

2. A fixture including a base having a bearing thereon, a housing tubular from one extremity adjustable both axially and rotatably through the bearing, means for holding the housing immovable in the bearing, a spindle axially movable in the housing and projecting outwardly beyond the tubular extremity of the latter, a cam shaft rotatably mounted in the housing, means holding said shaft against axial movement, a cam on said shaft in engagement with the extremity of the spindle remote from its outwardly projecting extremity adapted to move said spindle outwardly through the housing, said spindle being tubular from its outwardly projecting extremity for a portion of its length, the tubular spindle portion having opposed slots therethrough intermediate of its length, a pin transversely mounted in the

housing and extending through the slots, a spring in the tubular portion of the spindle extending between the pin and the base of said tubular portion holding the spindle against the cam, a button on the tubular end of the spindle, another bearing spaced from and in alignment with the first named bearing, an anvil supported by said other bearing for rotary adjustment between which and the button a workpiece is adapted to be held.
